UNITED STATES PATENT OFFICE

DANA X. BIBLE, OF LINCOLN, NEBRASKA

FOOTBALL BLOCKING PAD

Application filed February 14, 1930. Serial No. 428,413.

The invention relates to an athlete's protective body garment or harness, and more especially to the class of football blocking pads.

5 The primary object of the invention is the provision of a garment or pad of this character, wherein the ribs, kidneys, hips and tail bone or coccyx of a wearer are protected to a maximum degree, and by reason of the 10 water proof lining of said garment or pad there is avoided an increase of weight by absorption of perspiration, thus relieving discomfort in the wearing of such garment or pad.

15 Another object of the invention is the provision of a garment or pad of this character, wherein at certain points of the waist line area of the same there is provided a novel construction which is designed to coact with 20 football pants while being worn, so that irrespective of the position assumed by the wearer, the pants shall be prevented from slipping down or the garment or pad working upwardly on the wearer, as the pants will be 25 maintained in proper position and also the garment or pad held against normal tendency to slip upwards, thereby relieving the wearer of this constant annoyance which requires pulling and hauling at such pad and 30 pants with resultant diversion of the mind in this connection.

A further object of the invention is the provision of a garment or pad of this character, wherein the construction thereof is 35 novel in form, particularly with relation to the protective areas, and the means provided for retaining both the garment or pad and pants in proper position on wearer during activity in a game of football.

40 A still further object of the invention is the provision of a garment or pad of this character, which is extremely simple in construction, thoroughly reliable and efficient in its purposes, strong, durable, light in weight, novel in form, neat in appearance, and inexpensive to manufacture.

45 With these and other objects in view the invention consists in the features of construction, combination and arrangement of parts as will be hereinafter more fully de-

scribed, illustrated in the accompanying drawings showing the preferred embodiment of the invention, and pointed out in the claims hereunto appended. However, it is to be understood that changes, variations and 55 modifications may be made in the invention as come properly within the scope of the claims hereunto appended, without departing from the spirit of the invention or sacrificing any 60 of its advantages.

60 In the accompanying drawings:—

Figure 1 is a plan view of the garment or pad constructed in accordance with the invention.

Figure 2 is a fragmentary plan view looking toward the inner face of said garment or pad or reverse of that shown in Figure 1.

Figure 3 is a fragmentary sectional view taken on the line 3—3 of Figure 1.

Figure 4 is a fragmentary sectional view 70 on the line 4—4 of Figure 1.

Figure 5 is a fragmentary sectional view taken on the line 5—5 of Figure 1.

Similar reference characters indicate corresponding parts throughout the several 75 views in the drawings.

Referring to the drawings in detail, A, designates generally the garment or pad, comprising a waist enclosing body element preferably formed from an outer section 10, of 80 canvas, a padding 11, and an inner lining 12, the latter covering the padding and being formed from water-proof material of relative light textile, these being connected together marginally by stitching 13, to effect a unitary 85 structure.

The body element is cut and shaped to provide a contracted center or intermediate portion 14, and correspondingly side, front and 90 back covering portions 15.

One of the portions 15, carries at the outer face of the garment or pad A, to be at the front of the wearer, a buckle 16, while the other portion 15, on the same face of the garment or pad carries a strap 17, which adjustably coacts with the buckle for the fastening of the said garment or pad on and about the body of the wearer. It is to be understood 95 that other means for fastening the garment 100

or pad may be substituted for the buckle and strap if found expedient or desirable.

Extended from the lower edge of the garment or pad at the median of the contracted center 14, is a depending apron or tab 18, which constitutes a tail bone or coccyx guard or shield, and stitched or otherwise secured to the outer face of this apron or tab is a stiff fibre composition reinforcement 19, in the nature of a plate, which give a degree of rigidity to the same to protect the tail bone or coccyx of a wearer of the garment or pad.

Mounted on the outer face of the garment or pad A, preferably at the localities shown in Figure 1, of the drawings, are stiff fibre composition rib, hip and kidney guards or shields 20, 21, and 22, respectively.

At the waist line of the garment or pad A, on opposite sides with respect to the kidney guards or shields 22, and between the rib and hip guards or shields 20 and 21, are abutment ledges or arched supports, each comprising an arched stiff fibre composition outer plate 23, having a metal strip like backing 24, for reinforcement purposes riveted or otherwise secured thereto as at 25, the plate 23, being secured at its ends by stitching 26, or otherwise to the garment or pad A. Concealing the space or gap between the plate 23, and the garment or pad created by the arched formation of said plate, are covering pieces 27, preferably made from leather, although other material may be employed. These pieces 27, are preferably stitched at 28, to the garment or pad and plate marginally thereof.

It is to be understood that the fibre composition employed is of a character to give stiffness and impact resistance to the guards or shields wherever associated with the garment or pad.

The abutment ledges or arched supports are designed to project very substantially from the garment or pad A, at their points of location, and function to hold up the pants and to hold down the garment or pad A when the latter and pants are worn by a player of football or the like, as in the wearing of the pants a belt is usually employed outside of the same, which belt when embracing the waist of a wearer will lie immediately above these ledges or supports.

The garment or pad A, is worn outside of the underwear, should a player use the same, and an outer-garment, such as a jersey goes over the pad A, and the pants are then laced or buttoned up and a belt to hold the pants encircles the waist line of the wearer outside of the pad and jersey, which belt will rest above the ledges or supports and abut the same, thus holding the pants from working downwardly and also holding the pad A, from working upwardly, without regard to the position or posture of the wearer or in other words one garment holds the other, it being impossible when these are in proper

relation for one to work away from the other, the normal tendency of the pad A, being to work upwards on the body of the wearer. It will be apparent that there is no need for any form of connector for the pants with the pad A, or the use of separable fasteners of any description when associating the ledges or supports.

In the use of the garment or pad A, ease and comfort are maintained and also protection to the body of the wearer.

What is claimed is:

1. A pad of the character described, comprising a body embracing member formed with spaced relatively wide portions and an intermediate narrow portion, the latter constituting a juncture between the wide portions, a tab depending from the narrow portion, rib and hip guards carried at proper localities on the wide portions, kidney guards properly disposed on the narrow portion, outwardly arched plates on the member between the rib and hip guards at the waist line of said member, backing strips rearwardly of the plates, and closure strips secured at the arched edges of the plates and to the member, these plates being arranged outmost with respect to the kidney guards and disposed to extend in their spaced relation in a horizontal direction and to project very substantially outwardly from the member.

2. A pad of the character described, comprising a body embracing member formed with intermediate and outer portions, a tab depending from the intermediate portion, rib and hip guards carried on the outer portions, kidney guards carried on the intermediate portion, outwardly arched plates on the member between the rib and hip guards at the waist line of said member, backing strips rearwardly of the plates, and closure strips secured at the arched edges of the plates and to the member, these plates being arranged outwardly of the kidney guards and disposed to extend in their spaced relation in a horizontal direction and to project very substantially outwardly from the member, said closure strips with the plates constituting seats for a trouser supporting belt.

In testimony whereof I affix my signature.
